UNITED STATES PATENT OFFICE.

FRANK E. FLEMING AND WILLIAM E. DE VOE, OF DETROIT, MICHIGAN, ASSIGNEES,
BY MESNE ASSIGNMENTS, TO RILEY STOKER CORPORATION, OF WORCESTER,
MASSACHUSETTS, A CORPORATION OF MASSACHUSETTS.

ASH-DUMPING MEANS FOR UNDERFEED STOKERS.

Application filed December 24, 1920. Serial No. 433,011.

To all whom it may concern:

Be it known that we, FRANK E. FLEMING and WILLIAM E. DE VOE, citizens of the United States, and residents of Detroit, in the county of Wayne and State of Michigan, have invented certain new and useful Improvements in Ash-Dumping Means for Underfeed Stokers, of which the following is a specification.

10 Our invention relates to ash-dumping means for underfeed stokers, and particularly, in some of its aspects, to stokers in which the fuel-mass is moved longitudinally along the retorts so that the ash is dumped at the rear end of the furnace.

15 Among the objects of our invention are to provide a simple, efficient, easily operated and durable mechanism, comprising a dumping plate or platform, supporting means therefor and plate-operating means, all capable of easy installation, susceptible to ready adjustment to secure and maintain proper operating conditions, and affording facility of manipulation so that it may be 20 operated readily by one man.

25 In the drawings, wherein we have illustrated an embodiment of our invention, Fig. 1 is a fragmentary vertical section showing the rear portions of the retort and the associated dumping structure of an underfeed stoker equipped in accordance with our invention; Fig. 2 is an exterior side elevation of the dumping lever and associated parts; Figs. 3 and 4 are vertical sections on lines 30 3-3 and 4-4 of Fig. 5; Fig. 5 is a rear elevation of the dump mechanism, as applied in a furnace, with parts broken away; Fig. 6 is a section on line 6-6 of Fig. 3; Fig. 7 is a fragmentary view of the weighted 35 ends of the dump plates; and Fig. 8 is a perspective detail of a roller-cage.

40 It is well known practice in underfeed stokers to provide a battery of longitudinal retorts 20, arranged side-by-side, each retort having marginal tuyère blocks 21 and (in one make or furnace) the wall-ward or outer tuyère blocks 22 of the extreme retorts extending up the side walls of the furnace to well above the level of the tops 45 of intermediate tuyère blocks 21. The tops of all the tuyère blocks have a declination rearwardly, and under the action of the fuel feeding ram 23 (of usual construction and operation) the fuel bed is fed rearwardly

55 along the retorts over the dead-plate structure 24 (if one be provided) that lies immediately beyond the rear of the retorts, so that the ash spills onto the dumping platform 25 which can be moved to drop its load into the ash-pit 26 below. In general 60 the arrangement thus far described is old.

65 In the particular construction shown a transverse beam 27 supports the rear ends of the retorts 20 and dead plate 24, and from it, also, is supported the ash-dumping mechanism. A pair of brackets 28 secured to the beam near its ends, and as many supplementary intermediate brackets 29 as may be desired (in accordance with the length of the span between brackets 28) afford support 70 for a squared rock shaft 30 on which is mounted the dumping platform 25 that preferably is approximately balanced with respect to the shaft. Beyond one of the side walls of the furnace, the rock shaft 30 has 75 connection with an operating handle 67 by which it, and the dumping platform, may be rocked.

80 Naturally an ash-dumping structure is normally subject to hard usage, and it is 85 desirable not only that its elements be rugged, capable of standing such use and also the variations of temperature to which they are subjected, but that they be so mounted and arranged as most effectively to preserve 85 the straightness of the shaft, the alignment of its bearings and a constant freedom of shaft movement, thereby to prevent sticking or binding or undue wear on the shaft and other dump mechanism. Also the parts are 90 in the main, made readily replaceable individually without necessity for knocking down the entire dump structure in effecting a repair.

95 The dump plate structure or platform 25 is made of a series of rather narrow sections 32 extending fore-and-aft, each presenting a flat top to afford a load-bearing surface 31, and each mounted on the squared rock shaft 30 but all interlocked, so that, 100 without needless strain on the shaft, they are always maintained in line and effectively worked as a single plate. Each section 32 has a top member or floor-portion 33 with a strengthening web 34 extending centrally along its underside this web carrying a reinforced square hub 35 recessed or notched from its underside, as at 36, to fit

on the squared shaft 30. Each section also has a heavy counterweight block 37, with its rear surface curved on a rather short arc struck from the shaft center, each such block having one one side thereof a projecting squared rib 38 and on the other side thereof a corresponding groove 39. By these ribs and grooves all of the sections of the series constituting the dump plate structures are interlocked, so that they are held in accurate alignment and will move together without wearing on or loosening with respect to the shaft, and by arranging the side walls of the hub-notches and the rib-and-groove connections in parallelism as shown, one may readily slip any section 32 off of the shaft without disturbing the others.

The shaft 30 is mounted in appropriate roller bearings in its several brackets 28 and 29. At the proper bearing points the shaft has fitted thereon bushings 40 of cylindrical exterior form to bear on rollers 41, which are positioned in the bracket by a cage 42, consisting of semi-annular end pieces 43 and roller-spacing connecting-bars 44, so that the rollers work on the lower arcs or semi-circular race portions 45 of the various brackets, the ends of such races being overlapped by the outer margins of end pieces 43. Above such race each bracket has a slot 46 slightly narrower than the raceway-diameter so to provide shoulders 47 for retaining the cages in place, and such slot 46 is closeable by a dust cap 48 which has its ends shaped to slidably interfit with the slot-walls, snugly completing the bracket closure. The rugged roller-bearings thus provided work well in the dust and grit of the ash-pit.

While all of the brackets 28 and 29 are alike in their provision of bearings as described, it is very desirable, where more than two bearing brackets are provided, that only the end ones 28 thereof shall rigidly position their bearing-centers, any intermediate brackets being made of plural-piece construction for adjustment of the bearings. Therefore, while the end brackets 28 are of rigid single-piece construction, the intermediate brackets 29 are made of adjustable sections. Each such bracket 29 has a base portion 50 with a horizontal surface or seat 51 straddled by the bifurcated yoke 52 of the bracket-head the limbs of such yoke extending down over the sides of the seat. Between the seat and the yoke two complementary wedge members are disposed, the upper one, 53, having up-turned lugs 54 at its ends (Fig. 4) to position it against fore-and-aft displacement with respect to the yoke 52, and the lower wedge member 55 being preferably longer and having a plane bottom surface so that it may be slid along the seat 51. Preferably the meeting surfaces of the wedges are transversely corrugated as at 56, 56', so that when once adjusted they

tend to hold their interlocked position with such a grip that the plain bottom surface of the lower wedge 55 tends to slide along the seat 51 under strain, rather than the corrugated surfaces releasing.

It will be observed that the several bearings may be nicely adjusted to give the requisite alignment of the shaft-bearings and that, although the shaft is supported at a number of points adequately to sustain its load and to prevent its sagging, any slight warping or twisting of the shaft due to temperature change or to severe usage will not cause it to bind badly in its bearings, since the sections of the center brackets have a sufficient capacity for slight "come and go," or displacement, under such conditions, to automatically adjust themselves in some degree to slight distortions of the shaft, and further have the capacity for ready manual re-adjustment as the case may require. Furthermore, anyone of the brackets, or its bearing, may be removed independently of the others, for repair or replacement.

One end of the shaft 30 extends freely through the side wall of the furnace and through a supporting bracket 60 upon which, above the level of the shaft 30 the hand lever 67 is pivoted. In practice, for convenience, we prefer to make the shaft of two sections 30, 30', coupled near the side wall as at 30", but this is not essential. The hand lever 67, shown as standing in horizontal position, has connected to it a link 61, suitably curved as shown, the opposite extremity thereof having pivotal connection with a lever 62 that is adjustably fixed to the end of the shaft 30. Such lever has a split hub 63 with a toothed inner face 64 engaging a split, externally toothed bushing 65 that is mounted on the squared shaft 30', so that when the bolts 66 for the split-lever hub are tightened the parts are securely clamped to the squared shaft, but manifestly the shaft bushing may be adjusted in the lever as desired. When the bolts are loosened the leverage afforded is such as to give an ample range of dumping motion to the dump late structure, and yet to enable one man to operate the dump, when loaded, with ease. The handle may be toggle-locked to hold the dump in raised position by being thrown over the line of centers of lever 67 and link 61, as the curvature of link 61 permits, and as shown in dotted lines, Fig. 2.

While we have herein described in some detail a particular embodiment of our invention it will be apparent to those skilled in the art that changes in the features of construction and arrangement may be made without departure from the spirit of our invention and within the scope of the appended claims.

We claim:

1. A furnace-dumping platform structure,

- for a furnace providing a dump area, comprising a rock shaft of squared cross-section disposed to stand normally with a diagonal of its squared cross-section vertical, said shaft traversing said dump area, and a plurality of sections each having a relatively long, horizontal, load-carrying plate portion which is relatively thin, and a vertically disposed thicker counterweight block extending downwardly from the front end of said plate portion, a strengthening rib along the underside of the plate portion and extending to and joining the counterweight block, and a hub formed on said rib and located near the counterweight block, said hub having a diagonally-downwardly opening squared notch therein for engagement with the shaft.
2. A furnace-dumping platform structure, for a furnace providing a dump area, comprising a rock shaft of squared cross-section disposed to stand normally with a diagonal of its squared cross-section vertical, said shaft traversing said dump area, and a plurality of sections each having a relatively long, horizontal, load-carrying plate portion which is relatively thin, and a vertically disposed thicker counterweight block extending downwardly from the front end of said plate portion, a strengthening rib along the under side of the plate portion and extending to and joining the counterweight block, and a hub formed on said rib and located near the counterweight block, said hub having a diagonally-downwardly opening squared notch therein for engagement with the shaft, and inter-engaging means on adjacent sections arranged to be engaged and disengaged by displacement of the sections in a direction paralleling the notch-sides, whereby said sections may individually be slipped into or out of engagement with adjoining sections and the shaft.
3. A furnace ash-dump platform structure, comprising a shaft of non-circular section and a plurality of platform-sections each having a hub with a recess shaped similarly to the cross-section of the shaft for engagement with the latter by movement of the platform-section in a predetermined direction with respect to the shaft, adjacent platform-sections having detachably interengageable means arranged to be inter-engaged by movement of one said platform-section relative to another in the same direction that engages the first said platform-section with the shaft.
4. In a furnace ash-dump platform structure, the combination of a squared shaft and a plurality of platform sections arranged transversely of the shaft, each said section comprising a relatively long load-carrying plate portion and a relatively short counterweight portion and a square-notched hub, said counterweight portion provided on opposite sides with respective rib and groove surfaces paralleling the sides of the notch, whereby said sections may individually be slipped into or out of engagement with adjoining sections and the shaft.
5. An ash-dump structure for furnaces, comprising a rock shaft, a platform mounted on said rock shaft and supporting brackets for said rock shaft including brackets for supporting the shaft adjacent its ends and an intermediate bracket comprising a head section affording a horizontal saddle, a base section having a horizontal seat parallel therewith, and an interposed two-piece adjusting wedge structure slideable with respect to one of the parallel surfaces afforded by the saddle and seat, the confronting surfaces of said wedge sections being complementally corrugated.
6. In a furnace ash-dump structure, the combination of a rock shaft, bearings therefor, a dump platform carried thereby and shaft operating means comprising a hand lever, a link connected thereto, a crank-lever pivoted to said link, and means connecting said crank lever to said shaft comprising a part non-rotatably secured to said shaft and engaging, for rotary adjustment, a portion of the crank lever, and means for securing said crank lever on said part in adjusted position.

FRANK E. FLEMING.
